UNITED STATES PATENT OFFICE.

JULIUS BERKEY, OF GRAND RAPIDS, MICHIGAN.

DESIGN FOR A HOOK.

SPECIFICATION forming part of Design No. 24,539, dated August 13, 1895.

Application filed March 25, 1895. Serial No. 543,158. Term of patent 14 years.

To all whom it may concern:

Be it known that I, JULIUS BERKEY, a citizen of the United States, residing at Grand Rapids, in the county of Kent and State of Michigan, have invented and produced a new and original Design for Hooks; and I do hereby declare the following to be a full, clear, and exact description of the same, reference being had to the accompanying drawings, forming a part thereof.

The invention relates to a new and original design for hooks; and it consists in the peculiar shape, as shown in the accompanying drawings, wherein—

15 Figure 1 represents the design in perspective; Fig. 2, in top plan, and Fig. 3 in bottom plan.

The design as illustrated consists of the two straight portions A (shown in Fig. 3) 20 formed into a loop, as B, the turned-up tongue section C extending from the straight outer shank A and overhanging the shank. The section at the base of the part C at one side

is turned directly down, forward, and parallel with the shanks, and at a point on a plane 25 with the point between the ends of the part C it is turned horizontally outward into a loop D substantially circular.

The essential feature is the design for the hook having the straight side, the loop B, the 30 overhanging part C, the turned-under and forwardly-extending part c having a horizontal loop D located at a point on a plane between the ends of the overhanging part C, all as shown.

Having thus described the invention, what is claimed, and desired to be secured by Letters Patent, is—

The design for a hook, substantially as shown and described.

In testimony whereof I affix my signature in presence of two witnesses.

JULIUS BERKEY.
